US00D625291S

(12) **United States Design Patent**
Andre et al.

(10) **Patent No.:** US D625,291 S
(45) **Date of Patent:** ** Oct. 12, 2010

(54) **STAND**

(75) Inventors: **Bartley K. Andre**, Menlo Park, CA (US); **Daniel J. Coster**, San Francisco, CA (US); **Daniele De Iuliis**, San Francisco, CA (US); **Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Douglas B. Satzger**, Menlo Park, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/340,846**

(22) Filed: **Jul. 27, 2009**

Related U.S. Application Data

(63) Continuation of application No. 29/319,238, filed on Jun. 5, 2008, now Pat. No. Des. 597,081, and a continuation of application No. 29/319,154, filed on Jun. 4, 2008, now Pat. No. Des. 597,080.
